CLAIM

The ornamental design for a drawer handle, as shown and described.

DESCRIPTION

FIG. 1 is a front perspective view of a drawer handle;

FIG. 2 is a front elevation view thereof;

FIG. 3 is a bottom plan view thereof;

FIG. 4 is a top plan view thereof;

FIG. 5 is a left side elevation view thereof; and,

FIG. 6 is a right side elevation view thereof.

The broken line representations in the figures are for illustration only and form no part of the claimed design.
